UNITED STATES PATENT OFFICE.

HUGH D. BRUCE, OF RENTON, WASHINGTON, ASSIGNOR OF FIFTY PER CENT TO FRANK S. ULLOM, OF RENTON, WASHINGTON.

BUNK FOR LOGGING CARS.

Application filed January 13, 1927. Serial No. 160,815.

This invention relates to log bunks and chocks for use on railway cars and trucks.

The object of my invention is the provision of improved devices of this character which will be of strong and durable construction, efficient in operation, and convenient to adjust and control.

More specific objects and advantages of the invention will appear in the following specification.

The invention consists in the novel construction, adaptation and combination of parts hereinafter described and claimed.

In the accompanying drawings,—

Figure 1 is a view in longitudinal vertical section of devices embodying my invention, parts being broken away and parts omitted; Fig. 2 is an end elevation taken from the left hand side of Fig. 1; Fig. 3 is a fragmentary side elevation of the bunk shown in the preceding views; and Fig. 4 is a perspective view of a chock member shown detached. Fig. 5 is a view similar to Fig. 1 showing a modified construction of the beam controlling mechanism; and Fig. 6 is an end elevation, partly in vertical transverse section, of Fig. 5.

In said drawings, the reference numeral 10 represents the bunk generally, the same being, preferably, of the shape of a capital letter H in transverse section to afford a horizontal floor element 11 between two spaced apart wall elements 12. Said floor element 11 is provided with longitudinally disposed slots 13, one near each end of the bunk. Extending into each of said slots is the rib element 14 of a beam member 15 of a substantially T-shape in transverse section, the upper or bar portion 16 of a member 15 being of greater width than that of the slot 13 through which the rib extends.

The upper surface of the bar portion 16 is serrated to afford lengthwise of the same a series of triangular shaped teeth 17. In its opposite sides said bar is provided with grooves, such as 19, which serve as guideways for the chock studs to be hereinafter described. The guideways 19 extend from end stops, as 20, provided in proximity to the outer end 21 of the respective bar portion. The inner end of a beam is pivotally connected by means of a pin 22 to the bunk.

The beam is adapted to be swung about its pivotal connection 22 so as to be elevated to raise the teeth of the beam above the plane

of the top edges 12¹ of the wall elements; or lowered to have the teeth entirely below such plane.

As illustrated in Figs. 1 and 2, a beam is raised into the elevated position in which it is shown at the left hand side of Fig. 1 by means of a cam 23 engaging a bearing surface 24 of the rib element 14. Said cam is rotatably mounted upon a pin 25 whose ends are rigidly secured in the side walls of the bunk, and is actuated through the medium of an arm 26 provided on the cam hub, and a reach rod 27 extending from the arm 26 to an arm 28 of an operating shaft 29 which is journaled in a bearing provided in a side wall of the bunk near the end of the latter opposite to that near which the beam is located.

As shown in Figs. 2 and 3, a shaft 29 has rigidly secured thereto a peripherally toothed wheel 30 which is located between bifurcations of an operating lever handle 31 which is fulcrumed upon the shaft. Said handle carries a pawl 32 which is engageable with the wheel teeth when the handle 31 is employed for rotating the shaft 29 and the arm 26 to effect the turning of the cam 23 in its beam raising movement.

After serving to elevate the beam the cam is regulated to serve as a support for the beam, the bearing of the latter upon the cam should be in a vertical plane with the axis of rotation of the cam.

33 represents a dog for releasably engaging the wheel 30 when the cam is in its beam supporting position.

Provided for each beam is a chock 34 (Fig. 4) having a central body portion 35 and front and rear portions which are disposed in angular relation therewith substantially as shown in Figs. 1 and 4.

The chock's rear portion, hereinafter termed the heel, is slotted to enable the chock to straddle the bar element 16 of a beam, the bifurcations 36 of a chock at opposite sides of said bar element being provided with studs 37, one on each bifurcation 36, to extend into the respective grooves 19; whereby the chock is slidably and hingedly connected to the associated beam 100. A chock's front portion 38, hereinafter designated as the toe, has centrally of its width, a tapered extremity to afford a reliable engagement with the teeth of the beam member.

At its opposite sides, the toe is provided with protuberances or horn elements 39 which are adapted to seat upon the top edges 12¹ of a bunk. Excepting the horns, 5 the width of a chock is less than the distance between the side walls 12 of the bunk.

The modified construction, shown in Figs. 5 and 6, differs from that illustrated in Figs. 1 and 2, with regard to the beam elevating 10 means which in lieu of the cam, comprises toggle links 40—41 connected with each other by means of a pin 42, and connected with the beam 15 and bunk 10 by pins 43 and 44, respectively. In this instance, the 15 pivotal pin 42 which couples a pair of links serves to connect the reach rod 27¹ with operating means which may be similar to those illustrated and described with reference to Figs. 1 and 2, the corresponding parts being 20 denoted by similar reference characters.

The toggle links and the operating arm 28 therefor pertaining to a beam are so arranged and proportioned that when the arm 28 is in alignment with the reach rod 25 27¹ the toggle links 40 and 41 will be brought into positions to have the axes of their pivotal connections 43, 42, and 44 in a vertical plane, or in dead centers, so to speak, with the direction of the force of 30 gravitation tending to collapse the toggle link assembly.

In operation, the beams at both ends of a bunk are raised into positions such as occupied by the beam at the left hand side of 35 Figs. 1 and 5 to cause the teeth 17 of the beams to be above the plane of the upper wall-edges 12¹ of the bunk. A tier of logs is then loaded upon the bunk, the central logs resting directly upon the bunk and the 40 outer logs on the beams. The chocks are then pushed inwardly of the bunk into engaged relations with the logs so as to have the chock toes 38 engage the teeth 17 of the beams whereby the logs are reliably retained 45 by the chocks upon the bunk.

With the lower tier of logs thus secured, other logs may be piled thereon to complete the load.

When the logs are to be released for 50 dumping, the chock at that end of the bunk over which the logs are to be delivered is released by regulating the respective beam support—the cam 23, as in Fig. 1, or the toggle links 40 and 41, as in Fig. 5—to permit the beam to descend for withdrawing the teeth of the beam out of engageable relation with the chock.

When this occurs the horns 39 of a chock are brought into contact with the bunk wall edges 12¹, whereupon the lateral pressure exerted by the logs against the chock will cause the latter to be shifted outwardly, as from its dotted line position 34¹ for instance in Fig. 1 until the toe end of the 60 chock falls over the end of the bunk as rep-

resented by the chock shown in full lines at the right hand side of Figs. 1 and 5. The outward movement of a chock is limited by the studs 37 thereof encountering the stops 20 provided by the groove ends, one 70 at each side of the bunk.

When in its outward movement the horns of a chock travel beyond the bunk walls, the outer or toe end of the chock falls so as to have the chock entirely below the plane of 75 the top edges of the bunk walls, thereby rendering the chock incapable of obstructing the rolling or lateral sliding of the logs from the bunk.

While I have illustrated the invention in 80 embodiments now preferred by me, I do not wish to be understood as confining myself thereto except as limited by the appended claims.

What I claim, is,—

1. The combination with a bunk, and a chock arranged for movement vertically and longitudinally of the bunk, of manually controlled vertically movable means for effecting the elevation of the chock into a log-retaining position at selected positions longitudinally of the bunk.

2. The combination defined in claim 1 wherein the manually controlled means includes a toothed beam pivotally connected at one of its ends to the bunk, and adjustable devices engaging the other end of the beam 95 for elevating the same.

3. The combination with a bunk and a chock therefor, of vertically movable means 100 adapted when in its elevated position to entirely support the chock and when in a lower position to cooperate with the bunk for supporting the chock, said means also being adapted when in its elevated position to hold the chock in log retaining position, and means for elevating and lowering said vertically movable means.

4. In a bunk, a beam provided with a series of teeth in its upper surface, said beam being connected to the bunk for vertical movement, a chock coupled at one end thereof with said beam for relative longitudinal movement and means for elevating the beam to locate the teeth thereof in engageable relation with the other end of 115 said chock for releasably holding the chock in selective log retaining positions.

5. The combination with a bunk having spaced apart side walls, a chock having one 120 end thereof adapted to seat upon said side walls, a means adapted to be elevated into position to elevate the chock from its seating contact on the walls of the bunk and secure the chock in log retaining position, 125 and means to effect vertical movements of the first named means.

6. In a bunk, a beam having teeth in its upper surface and pivotally connected at one end thereof to the bunk, means engag- 130

ing the beam in proximity of its other end for elevating and lowering the same, and a chock slidably connected at one of its ends to the beam, the other end of the chock being formed to adapt the same to be supported upon the bunk and the beam when the beam is in its lower and upper positions respectively.

7. In a bunk, a chock arranged for horizontal movement longitudinally of the bunk and also for movement vertically thereof, said chock being provided with laterally directed horn elements engageable with the bunk and vertically movable means engageable with the chock for releasably retaining the latter at a selected position longitudinally of the bunk.

8. In combination, a bunk provided with side walls, a vertically movable beam disposed between said side walls, said beam being provided with a series of teeth in its upper surface, and a groove in each side of the beam, a chock having one end thereof bifurcated to straddle said beam and provided with means engaging the beam in the groove thereof, the other end of said chock being adapted to engage upon the top edges of the bunk walls and also with the beam teeth selectively when the beam is in its elevated position, and means for elevating the beam in its chock engaging position.

Signed at Seattle, Washington, this 4th day of December, 1926.

HUGH D. BRUCE.
